Beman

Application April 15, 1938, Serial No. 202,251

4 Claims. (Cl. 15—135)

The invention relates to brushes and more particularly to that type of brush sometimes called a fountain brush, wherein the brush is associated with a container for feeding a paste or liquid to the brush for spreading by the brush. The present application forms a continuation in part of my application, Serial No. 165,855, filed September 27, 1937, for Shaving brush.

An object of the present invention is to provide a brush of the character described which is particularly arranged for use as a shaving brush and for association with a collapsible tube of shaving cream, and wherein the means of connection between the brush is so arranged as to provide the attachment of substantially all of the various sizes of such tubes at present in common use.

Another object of the invention is to provide a fountain brush of the character described wherein the brush proper is connected to the discharge neck of a collapsible tube and wherein such neck is sealed both at its inner and outer annular surfaces to the brush support and the means provided thereby for conveying shaving cream to the brush.

A further object of the invention is to provide a shaving brush of the character above which is designed and constructed to catch soap and water drippings from the brush and prevent the running of such drippings onto the handle of the brush.

Still another object of the invention is to provide a fountain brush of the character described wherein a continuous sealed and unobstructed passage is provided for the shaving cream from the interior of the tube to the interior of the brush base.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a longitudinal sectional view of a brush constructed in accordance with the present invention.

Figure 2 is a perspective view of the brush as the same appears when ready for use.

Figure 3 is a perspective view showing the brush as the same appears when covered and set aside after use.

Figure 4 is a cross-sectional view of the brush base support taken substantially on the plane of line 4—4 of Figure 1.

Figure 5 is a slightly enlarged longitudinal sec-

tional view showing the mode of attachment of the brush support to a collapsible tube.

The brush of the present invention as depicted in the accompanying drawing, consists briefly of a brush proper 7 and a base support 8 therefor which is in turn provided with means 9 for connection to a collapsible tube 11 of material to be applied by the brush. In the present form of the invention the means 9 consists in part of an end portion 12 of a conduit 13 which extends from an end 14 of the base part and is arranged for insertion directly into the open neck end 16 of the tube 11. The conduit extends longitudinally through the support 8 and directly into the base 17 of the brush 7 and the inner end 18 of the conduit is preferably extended somewhat beyond the adjacent end wall 19 of the support, so as to discharge the contents of the tube in a portion of the brush base not rigidly secured in the support. In this manner, the conduit 13 extends at the end 12 directly into the interior of the tube 11 and forms a smooth, continuous and sealed passage for the tube contents to the opposite end 18 of the conduit directly in the lower body portion of the brush 7. The material when discharged from the end 18 of the tube will work its way through the brush bristles for applying at the outer surfaces 21 of the brush.

As an important feature of the present invention, the end 12 of the conduit is preferably tapered for ease of insertion into the neck of the collapsible tube and for tightly securing the conduit end within the tube neck. The taper also provides for the fitting of various size tube necks on the conduit end so that substantially any size tube in common use may be used. Preferably, in order to facilitate attachment of the tube to the conduit end and to provide a better seal between such end and the conduit neck, the end 12 is threaded so as to cause a penetration of the thread portions of the end into the relatively soft metal from which the neck of the collapsible tube is commonly constructed.

In addition to the connection of the tube neck to the conduit end 12, I prefer to also connect the tube neck directly to the body portion of the support 8, so that a more rigid connection with the tube is provided and a better seal with the tube neck is effected. To accomplish this latter connection, I arrange the support 8 adjacent the end 14 with a longitudinal bore 22 surrounding the conduit end 12 and preferably, thread the inside surface 23 of the bore for engagement with the threaded exterior surface 24 of the tube neck. Also preferably, the end 14 of the support is beveled in conformity with the upper end 26 of the tube leading to the neck 16, so that when the tube is screwed home in the support, as illustrated in Figure 1, the upper end of the tube will be snugly fitted against and within the support.

In attaching the neck of a collapsible tube to the connection means of the present brush, the neck of the tube may engage at various longitudinal positions on the conduit end 12, depending upon the internal diameter of the neck. Where this neck is of relatively small internal diameter, the same will be engaged by the tapered end 12 towards the extremity of such end and upon rotation relative to the support, will be threaded onto the conduit end 12 and expanded thereby into threaded connection with the wall 23 of the body to tightly secure the tube to the support 8. Where the tube neck has a larger internal diameter, the same will initially engage the tapered conduit end 12 at a more inwardly position and will consequently extend further into the bore 22 before the same is wedged between the tapered periphery of the conduit and the inner surface 23 of the bore. In this manner substantially all types and sizes of collapsible tubes having a discharge neck of the character described may be used in conjunction with the present brush, and in all of such cases, regardless of the size of the tube, a positive and fixed attachment and seal of the tube and support is provided.

The support 8 is preferably constructed of a plurality of sections 27 and 28 so as to facilitate the manufacture of the brush. As here shown, the section 27 is of substantially tubular form and is arranged to surround the base ends of the brush bristles and to provide a chamber 29 in which such bristles may be cemented. Preferably, the member is provided with an internal shoulder 31 adjacent the end 19 of the support, so as to confine the bristles and cement base therefor against removal from the chamber 29. The section 28 is preferably of cylindrical form and is provided with a reduced inner end portion 32 which is adapted for insertion into the sleeve 27 to abut the base of the brush bristles and define an end wall 33 for the chamber 29. Preferably, the conduit 18 which extends longitudinally through these sections, is provided with a shoulder 34 which is adapted to seat in a recess 36 formed in the end wall 33 of the section 8 and preferably, the shoulder 34 and the recess 36 are of non-circular form so as to prevent relative rotation of the conduit and brush support. In this manner, it will be seen that the cement used for securing the brush bristles in the body of the supporting member also operates to rigidly secure the several parts of the supporting member together. Preferably, the sections 27 and 28 are provided with curved annular surfaces 37 and 38 which are complementary to each other in forming a smooth, continuous annular concavity around the base 8 for improving the engagement of such base in the hand of the user.

As a further important feature of the present invention the end surface 18 surrounding the base portion 11 of the brush is preferably concave so as to provide a dish-shaped end of the support for catching soap and water drippings and the like from the brush and preventing such drippings from running onto handle portion of the brush. Preferably, I also provide a cover 39 for the brush when not in use and which may be readily attached to or removed from the brush as desired. As here shown, the cover 39 is in the form of an inverted cup having a portion 41 of the side wall adjacent the open end thereof ta-

pered and arranged to slidably fit a tapered annular wall portion 42 of the section 27 adjacent the surface 18. In this manner the cup may be slipped onto the section 27 or removed therefrom without the use of threads or other more cumbersome attaching means. Preferably, the outer end 43 of the cup is substantially flat, so as to enable the brush assembly to be inverted and supported on such surface, as illustrated in Figure 3, when the brush is enclosed by the cup and set aside after use.

I claim:

1. For use with a collapsible tube having an open neck end threaded exteriorly of said neck, a brush and base support therefor, a conduit carried by said support extending into the base of said brush and having a tapered portion extending exteriorly from said support for insertion into the open neck of said tube, an interior threaded portion in said support and surrounding said conduit portion adjacent said tapered portion and adapted to engage said tube neck as the latter is expanded by being forced onto said tapered portion of said conduit to cut new threads or modify existing threads to seal said neck to said support.

2. For use with a collapsible tube having an open neck end threaded exteriorly of said neck, a brush and base support therefor, a conduit carried by said support extending into the base of said brush and having a portion extending exteriorly of said support for insertion into the open neck end of said tube, said support having a threaded opening surrounding said conduit portion, said conduit portion being tapered and threaded for screwing into said tube neck for cutting threads into the inner surface of said neck and expanding the same into engagement with said threaded opening for cutting threads into or modifying the existing threads on the exterior of said neck for simultaneously sealing said tube interiorly and exteriorly to said conduit and support.

3. A brush, comprising, a plurality of bristles and a base support therefor having a part circumscribing the base of said bristles, a section having an end recess carrying said base support and surrounding said part, a second section fitted into said recess and extending longitudinally therefrom and abutting the base support to completely enclose the same, said sections being formed with curved annular surfaces forming a smooth annular concavity surrounding said sections.

4. A brush, a base support therefor comprising, a section surrounding the base of said brush, a second section extending into said first section and abutting the base of said brush and having a central axial opening and a non-circular depression adjacent said opening at the base of said brush, a conduit member extending centrally through said sections and communicated at one end with the interior base portion of said brush and having a radially extending portion adapted to fit into said non-circular depression, cutting threads on the inner surface of the opening through said second section, a tapered external surface on said conduit member adjacent its extension through said second body section, and external cutting threads on said surface.

ARCHIBALD S. BEMAN.
